UNITED STATES PATENT OFFICE

JESSIE LEE LYLE, OF DANVILLE, VIRGINIA

BUNCH-BUILDING AND BOBBIN-FORMING ATTACHMENT FOR SPINNING MACHINES

Application filed May 31, 1928. Serial No. 281,868.

This invention relates to a combined bunch builder and bobbin former for use with spinning machines, one of the objects of the invention being to provide simple and efficient mechanism of this character which will regulate the quantity of yarn left on quills from automatic looms, to properly shape the bobbins to be used in automatic looms, and to so wind the yarn on a quill as to hold it more securely at the nose, thereby to prevent it from sluffing off.

A further object is to provide a mechanism for positively and effectively building a satisfactory bunch of yarn at the base of the quill so that more yarn will be located at this point than is customary in present day spinning practice.

Another object is to provide a mechanism which can be applied readily to any spinning frame used in making fillings for automatic looms, said mechanism adapted to positively control the length and depth of the bunch.

A still further object is to provide mechanism having a new and novel arrangement of adjustments whereby the action of the several working parts can be regulated to meet the conditions under which the mechanism is used.

With the foregoing and other objects in view which will appear as the description proceeds the invention resides in the combination and arrangement of parts and in the details of construction hereinafter described and claimed it being understood that changes in the precise embodiment of the invention may be made within the scope of what is claimed without departing from the spirit of the invention.

In the accompanying drawings the preferred form of the invention has been shown.

In said drawings,

Figure 1 is a front elevation of the combined bunch builder and bobbin former, showing the relative positions thereof, the starting position of the former being indicated by broken lines.

Figure 2 is an elevation of one side of the bunch builder, the cams used in connection therewith being indicated by broken lines, the builder chain being removed.

Figure 3 is an elevation of the opposite side of the bunch builder.

Figure 4 is a plan view thereof.

Figure 5 is a plan view of the bobbin former.

Figure 6 is an elevation of a bobbin such as made by the apparatus constituting the present invention.

Referring to the figures by characters of reference 1 designates the builder arm of the bunch builder one end of which is connected to the base of a spinning frame (not shown) by means of the main bearing axle 2 located near one end of the builder arm. Thus the said builder arm takes the form of a lever having a long arm and a short arm, there being an extension arm 3 pivotally connected to the short arm and carrying a counterbalance 4 adjustably mounted and adapted to be held against sliding movement by a set screw 5 or the like. The extension arm 3 can be adjusted angularly relative to the builder arm 1 by means of a screw 6 extending through a lug 7 extending laterally from the short end of the builder arm, this screw constituting a support for the extension arm 3 as shown particularly in Figure 2.

One side of the builder arm 1 is formed with a longitudinal groove 8 constituting means for retaining and guiding a slide 9 along one longitudinal edge of which are arranged rack teeth 10. One end of the slide can be provided with an adjustable stop screw 11 adapted to limit the movement of the slide 9 toward the axle 2. A pulley 12 is mounted on the builder arm 1 near that end thereof remote from the axle 2 while another pulley 13 is mounted on the slide 9. A longitudinal shaft 14 is journaled in bearings 15 provided therefor on the lower portion of the builder arm 1 and secured to this shaft is a worm 16 which meshes constantly with some of the rack teeth 10, the lower portion of the builder arm 1 being cut away as at 17 to permit this engagement of the worm with the teeth. A brake screw 18 extends into one of the bearings 15 and may be provided with any suitable friction means not shown, for engagement with the shaft 14 so as to retard its rotation.

A ratchet wheel 19 is secured to one end of the shaft 14 and pivotally mounted on this shaft adjacent the ratchet wheel is a lever 20 having a laterally extending lug 21 adapted to work within a yoke 22 extending laterally from one end of the builder arm 1. One arm of this yoke has a stop screw 23 mounted therein and this stop screw cooperates with the other arm of the yoke for limiting the oscillation of the lever. A dog 24 is carried by one end of the lever and engages the periphery of the ratchet wheel 19. Thus when lever 20 is swung in one direction the dog will act to impart a slight rotation to the ratchet wheel 19 whereas, when lever 20 is swung in the opposite direction, the dog will slip over the teeth of the ratchet wheel. A take-up rod 25 is pivotally connected to lever 20, there being a series of apertures 26 any one of which is designed to receive the pivot pin 27.

An adjustable connection between the take-up rod and lever 20 is provided in the manner just described. The upper portion of the take-up rod is screw threaded as shown at 28 for engagement by nuts 29, this rod being mounted in a bracket 30 adapted to be secured to a stationary portion of a spinning frame (not shown).

Pivoted on the slide 9 between the pulley 13 and the axle 2 is a trip lever 31 having an offset end portion 32 carrying a roller 33. The other end portion of this lever has an arm 34 pivotally connected thereto at 35 and adapted to swing upwardly relative to the lever. Downward swinging movement of the arm, however, will result in the roller 33 and the adjacent end portion of the lever 31 swinging upwardly. The outer or free end of the arm 34 has its bottom portion rounded as shown at 36, this rounded portion coming to a knife edge 37 adapted normally to bear against a stud 38 extending laterally from the builder arm 1 close to the axle 2. Roller 33 is adapted to contact with a small cam 39 having preferably nine regularly spaced points shown at 40 in Figure 2. This small cam is preferably formed of the hub portion of the main cam 41 which, as shown in Figure 2, is formed with three peripheral depressions one of which is rounded, as indicated at 42 while the others are angular as shown at 43 and 44. The bottoms of all of these depressions are the same distance, radially, from the axis of rotation of the cam.

Arranged at one side of the builder arm 1 is a block 45 pivotally mounted, as shown at 46 and carrying a cam roller 47 adapted normally to bear against the periphery of the cam 41. An adjusting screw 48 carried by a bracket 49 on the builder arm 1 engages one end of the pivoted block 45 and by means thereof the roller 47 can be adjusted relative to the periphery of the cam 41.

A builder chain 50 is anchored at one end to the builder arm 1, it being preferably connected to a block 51 at one side of the builder arm close to the lever 20. This chain is looped about the pulley 13 and extends under pulley 12 and thence upwardly over a guide pulley 52 to the bobbin former shown in Figure 1. This bobbin former includes the usual rocker mechanism a portion of which has been shown at 53. A lever 54 is pivotally mounted, at one end, on the rocker mechanism as shown at 55 and has an outstanding lug 56 to which one end of the chain 50 is adjustably connected by means of a stem 57 projecting from the end of the chain, and through the lug 56, this stem being held in place by a nut 58 or the like. The chain bears constantly on the arcuate periphery 59 of the rocker mechanism. Lever 54 has a recess 60 in its lower edge adjacent the pivot 55 and pivotally connected to the lever adjacent the recess is an elongated arcuate shoe 61 adapted to be adjusted angularly relative to the lever by means of a clamping screw 62 extending through a slot 63 in the shoe. The arcuate lower edge of the shoe is adapted to ride on a small roller 64 extending from a fixed portion of the frame of the machine.

When the machine is operating the lever arm or extension 34 is in contact with the stud 38 and the roller 33 is in rolling contact with the small cam 39, as shown for example in Figure 2. The parts are so proportioned that when the roller 33 is thus located, the roller 47 will be clear of the cam 41. As the cam 39 rotates it imparts an oscillating motion to the arm 1 of the builder, this builder arm swinging about the axis of the axle 2, such movement transmitting a very short stroke to the ring rail (not shown) of the spinning frame and at the same time causing the dog 24 to impart an intermittent rotation in a clockwise direction to the ratchet wheel 19 and the shaft 14. This short stroke action set up by the cam 39 continues long enough to cause the desired small bunch of yarn to be formed on the base of the quill as shown by full lines at *a* in Figure 6 and as hereinafter more fully explained. The rotation of the worm 16 with the shaft 14 will cause the slide 9 to feed longitudinally, carrying the lever 31 with it until finally the free end of the extension arm 34 will slip from under the stud 38 and allow the roller 33 to drop out of contact with the cam 39 against which it has been held by the weight 4 and the pull of the chain 50. Following this action the roller 47 comes against the periphery of the cam 41 so that, instead of the short stroke set up by the cooperation of cam 39 and roller 33, a full stroke will be imparted to the ring rail due to the cooperation of cam 41 with roller 47. The worm 16 continues to shift the slide 9 and the rack teeth 10 as long as the builder arm 1 oscillates, and

during this movement, the pulley 13 moves toward the pulley 12 so that the chain 50 is gradually paid out. As this chain is thus paid out the ring rail (not shown) will gradually rise until the bobbins are filled to the desired height.

By providing a bobbin former such as shown for example in Figure 1 the full stroke of the bunch builder is prevented from being transferred to the ring rail while the lower portion of the bobbin is being wound. During the first part of the operation of the mechanism the chain 50, being drawn back or shortened, the former will be located with its parts positioned as shown by broken lines in Figure 1. At this time the roller 64 is within the recess 60 and the lever 54 with its shoe 61 is swung downwardly relative to the arcuate portion of the rocker mechanism. Consequently the chain 50 is permitted to move farther to the right, in Figure 1, than would otherwise be possible, this being due to the changed position of the lug 56 which is swung to the right as shown by broken lines in Figure 1. On each stroke of the bunch builder the lever 54 is moved to the left with the rocker mechanism and, during this movement, will come against the roller 64 and be swung outwardly away from the axis of rotation of the rocker mechanism. This abrupt swinging or lifting action continues on each stroke of the mechanism until the lever has been brought to its extreme position to the left as shown by full lines in Figure 1. During the latter portion of this movement the roller 64 will be engaged by the arcuate bottom surface of the shoe 61 so that the lever will not swing the rocker mechanism. The action of the rocker mechanism gradually shortens the stroke of the ring rail during the first strokes imparted by the main cam 41 to the bunch builder and each stroke is shortened more than the next preceding stroke as the motion of the lever 54 results in the roller 64 being engaged more and more by the curved edge of the shoe 61 after gradually passing off of the end wall of recess 60. Thus the bobbin is caused to fill out at the bottom as shown at *a* rather than to have a taper as indicated by dotted lines at *a'* in Figure 6, this latter arrangement being the one usually produced by mechanisms now in use. The curvature of the active edge of the shoe 61 is such as to throw a shorter radius of curvature in contact with the roller 64 as the ring rail nears the top of the bobbin. This action obviously shortens or takes up the chain 50 to a slight extent during each stroke and, consequently, the top of the bobbin is filled out as shown at *b* instead of with a long taper such as commonly produced and which has been indicated by dotted lines at *b'*.

Importance is attached to the fact that the cam 41 is so shaped as to cause the yarn to be wound slightly higher at the top of each third

stroke than on the two preceding strokes. This action causes the yarn to cross more rapidly at the nose of the bobbin on each third stroke and to form a tightly wound, slightly protruding nose which does not sluff off in the loom. This important action results from the use of the peripheral depressions 42, 43 and 44 heretofore mentioned. The innermost portions of all of these depressions are equidistant from the axis of rotation of the cam. When the depression 42 goes over the roller 47, said roller will move inwardly the full depth of the depression, as the depressions 43 and 44 are angular, the roller 47 cannot move thereinto the full distances. Instead the roller will bridge the innermost portions of the depressions as they pass thereover. Consequently two of the upward movements of the builder arm 1 of the bunch builder will be for the full depth of the depression 42 while the other upward movements will stop before the full depth is reached.

By providing the regularly spaced points 40 on the cam 39 and utilizing preferably nine of these points, (although this number is not essential) a more rapid crossing of the yarn wound on the quill results during the building of the bunch and in consequence thereof, the bunch will adhere more securely to the quill than would otherwise be possible.

For the purpose of effecting an adjustment between the trip lever 31 and the arm 34, an adjusting screw 65 may be extended into the lever 31 so as to constitute an adjustable stop for the arm 34.

What is claimed is:

1. Mechanism of the class described including a builder arm mounted for oscillation, a member movable thereon, a builder chain connected to the builder arm, cooperating means on the builder arm and member for forming a loop in the chain, means for oscillating the builder arm, means actuated by the oscillation of the builder arm for shifting the movable member to reduce the loop and pay out the chain, a bobbin former rocker mechanism, a connection between said mechanism and the chain, and means for automatically shifting said connection relative to the rocker mechanism while the chain is being paid out, thereby to retard the action of the rocker mechanism.

2. Mechanism of the class described including a bunch builder arm mounted for oscillation, a member movably mounted thereon, a builder chain connected to the builder arm, means carried by the member and builder arm for maintaining a loop in the chain, separate cams, means on the movable member for engagement by one of the cams to oscillate the builder arm, means actuated by the oscillation of the builder arm for shifting the movable member to reduce the loop in the chain and pay out the chain and to release the cam engaging means from active

cooperation with its cam, means carried by the builder arm for engagement and actuation by the other cam following said release, thereby to oscillate the builder arm at a different speed, a bobbin former rocker mechanism, a shiftable connection between said mechanism and the chain, and means for automatically advancing said connection while the chain is being paid out, thereby to retard the movement of the former mechanism.

3. Mechanism of the class described including a bunch builder arm mounted for oscillation, a member movably mounted thereon, a builder chain connected to the builder arm, means carried by the member and builder arm for maintaining a loop in the chain, separate cams, means on the movable member for engagement by one of the cams to oscillate the builder arm, means actuated by the oscillation of the builder arm for shifting the movable member to reduce the loop in the chain and pay out the chain and to release the cam engaging means from active cooperation with its cam, means carried by the builder arm for engagement and actuation by the other cam following said release, thereby to oscillate the builder arm at a different speed, a bobbin former rocker mechanism, a shiftable connection between said mechanism and the chain, and means actuated by the movement of the rocker mechanism as the chain is paid out for variably advancing the connection between said mechanism and the chain thereby to variably retard the movement of the rocker mechanism while the chain is being paid out.

4. Mechanism of the class described including a bunch builder arm mounted for oscillation, a member movably mounted thereon, a builder chain connected to the builder arm, means carried by the member and builder arm for maintaining a loop in the chain, separate cams, means on the movable member for engagement by one of the cams to oscillate the builder arm, means actuated by the oscillation of the builder arm for shifting the movable member to reduce the loop in the chain and pay out the chain and to release the cam engaging means from active cooperation with its cam, means carried by the builder arm for engagement and actuation by the other cam following said release, thereby to oscillate the builder arm at a different speed, a bobbin former rocker mechanism, a lever fulcrumed thereon, an arm extending from the lever engaging the chain, an adjustable shoe carried by the lever, and fixed means in the path of the lever and shoe for advancing the lever arm relative to the rocker mechanism at variable speeds while the chain is being paid out, thereby to variably retard the movement of the rocker mechanism.

In testimony that I claim the foregoing as my own, I have hereto affixed my signature.

JESSIE LEE LYLE.
